(57) **CLAIM**

The ornamental design for a wall mount bracket, as shown and described.

DESCRIPTION

FIG. 1 is a perspective view of a wall mount bracket showing the design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions shown in dotted lines do not form part of the design. The dot-dash-dot line does not form part of the design and is included for illustrative purposes only to indicate a boundary of the design.
